UNITED STATES PATENT OFFICE.

PAUL PONDORF, OF GOESSNITZ, GERMANY.

APPARATUS FOR TESTING CARTRIDGES.

SPECIFICATION forming part of Letters Patent No. 639,432, dated December 19, 1899.

Application filed March 8, 1899. Serial No. 708,214. (No model.)

To all whom it may concern:

Be it known that I, PAUL PONDORF, manufacturer, a subject of the Emperor of Germany, residing at Goessnitz, Saxe-Altenburg, German Empire, have invented certain new and useful Improvements in Apparatus for Testing Cartridges; and I do hereby declare the following to be a full, clear, and exact description of the invention, such as will enable others skilled in the art to which it appertains to make and use the same.

This invention relates to means for testing the condition of the firing or flash holes of metal cartridge-cases; and the essential features of the said invention may be briefly stated as follows: At a suitable part of the drilling-machine are arranged two needles, each of which is movable endwise independently of the other and is provided with a projection or stop rigidly secured to or formed integral therewith. The diameters of the lower ends of the said needles are equal to the diameters of the firing or flash holes to be drilled, while they are formed to a gradual taper or increase in thickness somewhat toward the rear. Now, when it happens that the requisite holes in the cartridge-case have not been made in consequence of the drill having broken, for example, or have not been made deep enough, or are too narrow or too wide, one or both of said stops, as the case may be, is or are either arrested sufficiently far back or allowed to proceed a sufficient distance forward to set in operation certain arresting or locking mechanism by means of which the drilling-machine is thrown out of gear and stopped. If, however, the two firing or flash holes of the cartridge-cases being tested are bored to the required dimensions, both needles will enter the cartridge-case for such a distance as will cause them to be arrested in a predetermined intermediate position, when the stops will check the locking or arresting mechanism and prevent its coming into operation.

By the arrangement of parts hereinbefore described the drilling-machine can only remain in uninterrupted operation so long as the drill works in a uniform and satisfactory manner, while the entire machine comes to a standstill immediately a single article in course of treatment proves to be defective.

In the accompanying drawings, which represent a flash or firing hole drilling machine fitted with an arrangement constructed according to the present invention for carrying out the novel operation above described, Figure 1 is a side elevation of the drilling-machine. Fig. 2 is an enlarged detail view illustrating the arrangement of the combined needles and stops. Fig. 3 is an end elevation of parts, drawn to a reduced scale and illustrating more particularly the strap-guide. Fig. 4 is a plan of the drilling-machine, and Fig. 5 is a detail view of the parts of the arresting mechanism acted upon by the stops.

In the several figures, in which like parts are indicated by similar letters of reference, the parts of the machine for fastening or mounting the cartridge-cases in position, for moving and centering the mounting, clamping, or gripping device, and for operating the drills are only shown in outline, as said parts are common to existing machines of this class and which are well known, so that they do not come within the scope of the present invention.

The drilling-machine, together with the above-mentioned apparatus for testing the condition of the flash or firing holes, is erected upon a base or bed plate *a* and carries upon its shaft *b'* a gripping or clamping device or holder *b*, wherein the cartridge-cases to be operated upon are inserted and securely locked or clamped in position at 1 by means of any suitable contrivance. Motion is imparted to the shaft *b'* from the strap or band *c* through the medium of the shaft *b³*, worm *b²*, worm-wheel *b⁴*, Fig. 3, and a toothed segment *z*, mounted on the shaft or spindle *f* of the said worm-wheel, which segment gears with the toothed wheel *z'* on the shaft *b'* and at each revolution of the shaft *f* turns the said wheel for a distance equal to one-sixth of its circumference, so that consequently the cartridge-case-gripping device *b* is also turned sixty degrees at each revolution of the shaft.

The toothed segment *z* is a wheel having teeth on a part only of its periphery. It is not fully shown, as any approved mechanism can be used which will rotate the shell-holder *b* intermittently.

The cartridge-cases placed in the holder at 1 successively take up their position in front

of the two drills c , as at 2 and 3, and are here provided with firing or flash holes in the well-known manner, after which the cases move up to the testing-needles at 4, where the condition of their firing or flash holes is ascertained, and are lastly removed from the gripping device or holder.

The test is performed by means of the following arrangement of parts: Upon a suitable part of the frame of the machine are provided two slides or carriages d d' , which carry needles d'' d''' , by means of which the holes are tested, and these needles are controlled by springs d^4 d^5 , which springs constantly tend to press the said carriages in the direction of the gripping device. During the period in which the said gripping device turns the carriages d d' are held in their rearward or retracted position by means of an eccentric a'' , mounted upon the shaft f , which, through the medium of the lever-arm b'' and the intermediate piece or pusher d^6 , forces back the said carriages d d' , in doing which it overcomes the resistance of the springs d^4 d^5 . When, however, the said eccentric a'' leaves the position in which it is shown in Fig. 1 in continuation of its revolution, the springs d^4 d^5 push forward the carriages d and d' toward the clamping device or holder b , the motion of which has in the meantime been arrested, and in so doing move forward the intermediate piece or pusher d^6 and the lever-arm b'' , and the needles d'' d''' are now caused to enter the firing-holes with the following results: If the firing-holes have been bored normally—that is to say, of the required dimensions—the tapering needles d'' will enter said holes to a predetermined depth and be thus arrested in a predetermined intermediate position, with the result that the stops e e' , projecting from the carriages or slides d d' , will likewise be arrested in a given intermediate situation, the dimensions of the parts being so proportioned that the said stops e e' when in this intermediate position shall exactly be facing the front ends of the two slides h h' . At each revolution of the shaft f these slides are moved once toward the carriages d d' , inasmuch as the cam f^2 once in every revolution releases the double-armed lever g' , engaging with the noses or tappets k k' in the rear, thereby allowing the springs h^2 h^3 to come into operation. When the stops e e' take up the intermediate position above described, which indicates that the firing or flash holes have been drilled in a proper manner, the ends of the two slides h h' come against the corresponding ends of the stops e e' , and the mechanism hereinafter described, by means of which the machine is arrested in case of defective drilling is prevented from coming into operation, while the cam f^2 by means of its rise immediately pushes the two slides h h' back into their rearward or retracted position even before the needles d'' d''' have had time to leave the drilled holes after the completion of the test. If, however, owing to the

defective operation of the machine no holes have been drilled at all or they have been made too wide or too narrow, or if there should be any other defect in one of the holes, or if both holes are defective from some cause, then, according to circumstances, one or both of the needles d'' will either be prevented from entering the hole or holes far enough or will be allowed to advance too far, as the case may be, the result in all cases being that both needles will fail to stop precisely in the intermediate position above described.

The operation of the mechanism forming the subject of the present invention will in principle be the same in all cases without regard to the precise nature of the flaw discovered, and it will therefore suffice herein to describe only the case exemplified in Fig. 4, in which neither of the firing-holes has been partially or entirely formed in consequence—for example, of the perforating tool or drill having become broken. In this case the needles d'' cannot enter the cartridge-cases, and therefore the stops e e' remain in the position represented in Fig. 4. When the cam f^2 , in the revolution of the shaft f , releases the lever g' , and consequently the slides h and h' , these slides are driven by the springs h^2 and h^3 toward the sliding carriages d d' without meeting with any resistance on the part of the stops e e' . The slides h h' therefore advance until the inclines l l' meet the incline m of the fork-shaped guide of the strap or band o , and in the meantime the spring-catches i i' have taken up their position beyond the vertical pin of the double-armed lever g . As the shaft f continues to revolve, carrying with it the cam f^2 , this cam, through the medium of the lever g , moves the catches i i' and also the slides h h' farther toward the carriages d d' , so that the said inclines l l' force back the incline m and shift the strap guide or fork n , which, assisted by the weight g^2 , transfers the strap o to the loose pulley s , thereby automatically throwing the whole mechanism out of gear and stopping the machine.

What I claim is—

1. In apparatus for testing cartridge-shells, the combination, with mechanism for stopping the machine to which the testing apparatus is applied provided with a slide for actuating it, and means for reciprocating the said slide; of a slidable carriage carrying a testing-needle and provided with a stop which arrests the said slide when the said testing-needle has permitted the carriage to move to a prearranged extent, thereby preventing the said stopping mechanism from being operated to stop the machine, substantially as set forth.
2. In apparatus for testing cartridge-shells, the combination, with a slidable carriage provided with a stop and carrying a testing-needle; of a slide arranged crosswise of the path of the said stop, mechanism for stopping the machine to which the testing apparatus is applied controlled by the said slide, and means

for reciprocating the said slide, said stopping mechanism being operated whenever the said slide misses the said stop, substantially as set forth.

- 5 3. In apparatus for testing cartridge-shells, the combination, with a slidable carriage provided with a stop and carrying a testing-needle having a tapered point which will enter the normal firing-hole of the shell to a pre-
10 arranged extent and then arrest the said carriage; of a slide arranged crosswise of the path of the said stop, mechanism for stopping the machine to which the testing apparatus is applied controlled by the said slide, and
15 means for reciprocating the said slide, said stopping mechanism being operated whenever the said slide misses the said stop, substantially as set forth.

4. In apparatus for testing cartridge-shells, the combination, with a slidable carriage provided with a stop and carrying a testing-needle; of a slide arranged crosswise of the path of the said stop, a spring pressing the slide toward the carriage, means for retracting the slide intermittently, mechanism for stopping the machine to which the testing apparatus is applied controlled by the said slide, and driving devices operating to move the slide to an additional extent toward the carriage
25 whenever the slide misses the said stop, thereby constraining the said slide to operate the said stopping mechanism, substantially as set forth.

5. In apparatus for testing cartridge-shells, the combination with a slidable carriage pro-

vided with a stop and carrying a testing-needle; of a slide arranged crosswise of the path of the said stop, a spring pressing the slide toward the carriage, means for retracting the slide intermittently, mechanism for stopping the machine to which the testing apparatus is applied controlled by the said slide, a driving-lever provided with a projecting pin, a spring-pressed catch carried by the said slide and engaging automatically with the said pin whenever the slide misses the stop, and means for oscillating the said lever, said lever operating to move the said slide to an additional extent toward the carriage and thereby constraining the slide to operate the said stopping mechanism, substantially as set forth.

6. In apparatus for testing cartridge-shells, the combination, with two independently-slidable carriages arranged side by side, each carriage being provided with a stop and a testing-needle; of two independently-slidable slides arranged side by side and crosswise of the paths of the respective stops, springs pressing the slides toward the carriages, means for retracting the slides simultaneously, and mechanism for stopping the machine to which the testing mechanism is applied operatively connected with each said slide and controlled by it, substantially as set forth.

In testimony whereof I affix my signature in presence of two witnesses.

PAUL PONDORF.
